DISCHARGE VESSEL WITH SUBDIVISION
OF VOLTAGE

Johannes Gijsbertus Wilhelm Mulder and Jacob Hermannus van der Tuuk, Eindhoven, Netherlands, assignors, by mesne assignments, to N. V. Philips Gloeilampenfabrieken, Eindhoven, Netherlands, a Dutch company

Application October 26, 1933, Serial No. 695,358
In Germany November 2, 1932

9 Claims. (Cl. 250—27.5)

To increase their capacity to withstand high voltages, it has been proposed to provide high tension discharge vessels with conducting members which are distributed about the discharge path, and partly or wholly surround the latter annularly and with given spacings. A particularly advantageous form of constructing such members which subdivide the voltage applied across the electrodes is by making them in the 10 form of metal rings forming part of the wall of the vessel.

To insure even distribution of the voltage, condensers are preferably connected in parallel with the individual sections of the discharge path. It 15 has been found that discharge tubes constructed and connected in this manner, although extremely compact, are capable of withstanding the highest voltages, so that it is possible to use, even for extremely high voltage discharges, vessels having 20 a gaseous filling.

According to the invention, the condensers connected in parallel with the individual sections of the discharge path are arranged to annularly surround the discharge vessel proper so that when a 25 plurality of potential subdivisions is provided the condensers constitute together a closed, and preferably cylindrical body. Each of the condensers may advantageously consist of a cylindrical ring of a highly insulating material such as porcelain 30 or artificial resin, the annular body being provided with two separated grooves which are concentric with the axis of the cylinder and extend from opposite ends of the annular body. These 35 annular grooves, the walls of which are approximately parallel to each other, are provided on these walls with a good conducting layer. This layer may be made, for example, by means of a metal extruding process. The metal coatings of two operating grooves constitute the two armatures 40 of one cylindrical condenser. The condensers are secured in position, either by means of resilient rings engaging the wall of the discharge vessel and also establishing electrical contact with the metal bodies used to subdivide the 45 voltage, or the various condensers may be held in position by pressure by means of two end hoods or rings secured to the ends of the tube. The conductive connection between the coatings of two 50 adjacent condensers is brought about by a proper extension of the metal coatings or by the interposition of annular metal conductors. The end hoods holding the condensers together may be secured in position by means of a screw thread. For 55 this purpose preferably portions of the screw

threads of the standard Edison base of the tube which engage the end hoods can be used.

In order that the invention may be clearly understood and readily carried into effect one form of construction of a discharge vessel according to 5 the invention will now be described more fully with reference to the accompanying drawings, in which

Figure 1 is a side view partly in section showing one embodiment of the invention. 10

Figure 2 is a cross-sectional view of Fig. 3 showing the attachment of the rings.

Fig. 3 is a sectionized side view showing the attachment of the rings.

The preferably cylindrical envelope 1 of the 15 discharge vessel (Figure 1) carries at its two ends, through which the electrodes are introduced into the tube, two hoods 2 and 3 preferably provided with Edison bases 4 and 5. Suitably supported from the upper end of the vessel and with its two 20 ends electrically connected to the two terminals of the base 4 is an incandescent cathode 30. Suitably supported from the lower end of the vessel and electrically connected to one of the terminals of the base 5 is an anode 31. The glass wall is 25 interrupted by interposed metal rings 6, 7, 8, 9 sealed to the glass wall so as to insure a complete vacuum within the tube, the wings surrounding the discharge path for the subdivision of the voltage. 30

Connected to the metal rings are cylindrical or annular condensers 10, 11, 12, and 13. The uppermost condenser 10 being shown in section. The annular condenser body is provided with two grooves 14 and 15 which are separated from each 35 other by the insulating material of the annular body. The walls of these grooves are coated with a conductive layer shown in dotted lines 28. The individual cylindrical condensers are held together by end hoods 16 and 17 screwed on to the thread 40 of the Edison bases 4 and 5.

Figures 2 and 3 show a different manner of attaching the condenser rings. In contradistinction to the embodiment shown in Figure 1, the separating surfaces of the individual rings intersect the metal instead of the glass parts of the discharge vessel. 45

18 designates a metal member of the envelope of the discharge vessel, to the edges of which are sealed the adjoining glass parts 19 and 20. 50 The metal ring 18 is provided with a groove in a plane perpendicular to the axis of the tube and in which groove rest two resilient metal wires 21 and 22. The wires 21 and 22 are stretched along the metal part 18 and secured to a metal 55

ring 23 which is thus held centered relative to the metal member 18. Condenser bodies 28 and 27 are situated on either side of the ring 23. The coating 28 of the condenser 28 is in contact with the ring 23, and in the same way the coating 29 of the condenser 27 is in contact with the opposite side of the ring 23. The two condensers are consequently connected in series by the ring 23. Thickened edges 24 and 25 of the ring 23 prevent a lateral displacement of the condenser ring.

Again in this construction, the entire system of the piled condenser annuli may be held together by hoods screwed on to the tube ends. The metal wires 21 and 22 which effect the centering, also serve for the electrical connection of the condensers to the metal members of the tube wall.

What we claim is:—

1. In combination, a high tension electric discharge tube having a gaseous filling, two electrodes in said tube and electrode chambers therefor, a discharge channel connecting said electrode chambers, a plurality of conductive members insulated from each other and distributed along the length of the discharge channel, and a protective cylinder formed of a plurality of sections surrounding said tube, each section of said cylinder comprising a condenser, the opposite armatures of adjacent condensers being electrically connected with each other so that all condensers are connected in series, the connecting point of adjacent condensers being electrically connected to one of said conductive members.

2. A protective cylinder for electric discharge tubes comprising a plurality of sections each formed of a ring-shaped body of insulating material, each body comprising two substantially concentric grooves, the two grooves extending from opposite ends of said body through a substantial part of said body and partly overlapping each other, and a conductive coating on the surface of each of said grooves, said coating extending over at least a portion of the corresponding end surfaces of the section.

3. A protective cylinder for an electrical discharge tube comprising a plurality of sections, each section comprising a ring-shaped condenser, means provided on the end surfaces of said condensers for electrically connecting two successive condensers, said means including a disc member interposed between adjacent condensers, and conductors secured to said disc member and forming outside electrical connecting members for the common point of adjacent condensers.

4. In combination, an electrical discharge device and a protective cylinder surrounding same, said discharge device comprising an envelope, and means disposed along said envelope for subdividing the potential, said protective cylinder comprising a plurality of sections, each section comprising an annular condenser body, means disposed on the end surfaces of said annular condenser body for electrically connecting two successive condensers, said means including a disc member interposed between adjacent bodies, and conductors secured to said discs and connecting same to the potential-subdividing means of said tube.

5. In combination, a high tension electric discharge tube comprising an envelope, a gaseous filling and electrodes therein, said envelope having alternating glass parts and circumferentially grooved metal parts, a protective cylinder surrounding said tube and composed of sections, the number of which exceeds by one the number of said metal parts, each section comprising a condenser body of dielectric material, said body having two grooves which are concentric with the cylinder and are recessed from opposite ends of the sections, conductive layers on the walls of said grooves, said layers forming the armatures of the condenser, a metal ring interposed between adjacent sections and interconnecting adjacent condensers, and means securing and electrically connecting said rings to opposing metal parts, said means comprising two wires, each connecting two inner circumferential points of the ring and symmetrically disposed with respect to the axis of the cylinder, said wires engaging the circumferential groove of the corresponding metal part.

6. An electric discharge device comprising an elongated container, a protective cylinder surrounding said container and composed of a plurality of similarly shaped sections mounted in axial alignment with each other, end members secured one at each end of said container, said end members retaining said sections in position.

7. An electric discharge device comprising an elongated container, electrodes mounted therein, contact screw caps secured one to each of the opposite ends of said container and electrically connected to the adjacent electrodes, a protective cylinder comprising a plurality of equally shaped sections mounted in axial alignment with each other and surrounding said container, and end members secured to each of said screw caps and retaining in position said sections.

8. An electric discharge device comprising an elongated envelope, electrodes mounted therein, a plurality of conductive members equidistantly disposed along said envelope, a protective cylinder surrounding said envelope, said cylinder being composed of a plurality of sections, each comprising a condenser, said sections being interconnected by interposed ring-shaped discs, said discs having thickened edges between which are held the adjacent ends of two sections, said discs being electrically connected with opposing conductive members, and terminal members secured to each end of the tube and preventing axial displacement of said sections.

9. In combination, an electric discharge device comprising an elongated envelope and electrodes therein, a plurality of conductive members disposed along said envelope subdividing the envelope into a plurality of sections, and a plurality of series-connected, ring-shaped condensers arranged in alignment with each other to form a composite tubular member surrounding the discharge device, each of said condensers being connected to two successive conductive members and in parallel to one of the sections of the envelope.
